ATOMIZING OIL BURNER

Gaylord H. Wotring, Bridgeport, Conn., assignor
to General Electric Company, a corporation of
New York

Application February 24, 1940, Serial No. 320,567

5 Claims. (Cl. 158—76)

The invention relates to atomizing oil burners, and provides an improved form of automatic oil burner of the conversion type in which a stream of atomized oil is discharged into a stream of combustion air at the burner nozzle and which may be installed for projecting flame into furnace combustion chambers of many different forms and sizes.

The principal object is to provide improved means for controlling the shape or form of the atomizing oil burner flame so as to enable the flame shape or form to be properly "tailored" to fit the form and size of the furnace combustion chamber, and thereby more readily obtain quiet, reliable, and efficient heating operation.

In the improved form of oil burner embodying the present invention, the rotational and linear momentum components of the combustion air stream issuing from the burner nozzle and carrying the atomized oil stream therewith are influenced by different adjustable parts of the apparatus that act successively on the air stream, the first as to direction and the second as to amount, to produce the desired shape or form of the flame resulting from the combustion of the atomized oil. When the linear momentum component of the combustion air stream is made relatively large and the rotational component thereof relatively small an elongated relatively narrow flame will be produced which is suitable for furnace combustion chambers that are long and narrow, while with the proportions of the linear and rotational components reversed, a relatively short wide angle flame will be produced which is suitable for furnace combustion chambers that are short and wide. Furthermore, by intermediate proportioning of the linear and rotational components of the combustion air stream and at the same time varying the rate of air flow and the supply of atomized oil thereto, the form and shape of the burner flame may be conformed to furnace combustion chambers of many other forms and sizes. The flexibility thus obtained in shaping the flame by means of the present invention enables the improved conversion oil burner to be applied more satisfactorily and efficiently to the various sizes and forms of boilers and furnaces ordinarily employed in domestic heating service with the minimum modification or reconstruction of the furnace combustion chamber.

A preferred form of the invention embodied in an automatic atomizing oil burner of the conversion type adapted for domestic heating service is illustrated in the accompanying drawing in which Fig. 1 is a side view of the improved burner partly in section to reveal the interior construction; Fig. 2 is a front view of the burner shown in Fig. 1 also partly in section to show more clearly the combustion air inlet opening into the burner nozzle; Fig. 3 is an enlarged top view of the burner nozzle shown partly in section to illustrate more

clearly the detail construction thereof; and Fig. 4 is a perspective view from the rear of the burner nozzle shown in Fig. 3 which more clearly shows the cooperating relation of the improved air rotational and linear momentum control parts.

As shown in Fig. 1 the improvements of the present invention are embodied in an automatic oil burner of the conversion type having the improved unit construction which is fully described and claimed in the patent application of Aldo Macchi, S. N. 320,557, filed concurrently herewith. In this burner unit construction, the electric motor driven blower 11 and air and oil supply means 12 together with suitable ignition and automatic control elements are mounted within an enclosing jacket or casing 10 which is partly broken away in Fig. 1 to indicate the presence of these elements. The burner combustion air supply nozzle 15 which is provided with an enlarged lateral air inlet scroll casing 16 as more clearly shown in the enlarged views of Figs. 3 and 4 is removably mounted upon the upright wall 17 with which the removable jacket or casing 10 cooperates to enclose the burner operating elements. Suitable mounting lugs 18 are provided for receiving the bolts 19 by means of which the combustion air nozzle 15 is removably mounted on the outer side of the upright wall 11. Thus the wall 17 serves to close the open end of the enlarged lateral air flow scroll 16 when the nozzle 15 is mounted in proper operating relation on this burner unit wall.

As indicated in Figs. 1, 2 and 3 combustion air under pressure is supplied from the electric motor driven blower 11 to the combustion air nozzle 15 through an elongated rectangular shaped opening 20 which is formed in the wall 11 so as to discharge the air under pressure into the upper part of the enlarged lateral air flow scroll 16. The outlet duct 11a of the electric motor driven blower 11 preferably is sealed to the upright wall 17 around the edges of the air inlet opening 20 by means of a resilient gasket 21 formed of felt or other suitable material.

In accordance with the present invention the separately adjustable and successively acting air flow control means are provided, the first for influencing the rotational, and the second for influencing the linear momentum component of the combustion air stream discharged from the air nozzle 15. In the preferred form of the invention illustrated in the drawing an adjustable flame shaping baffle 25 is located inside of the air flow scroll casing 16 adjacent the top thereof and directly in front and preferably to one side of the air inlet opening 20, as shown in Fig. 4, so as to control the rotational components of the air flow from the inlet opening 20 through the lateral scroll casing 16 and into the combustion air nozzle 15. The flame shaping baffle 25 is shown mounted upon an adjusting threaded shaft 26

which extends through an opening in the upper end wall of the scroll casing 16 and is maintained in its adjusted position by means of the lock nut 27. Thus the angular position of the flame shaping baffle 25 inside the scroll casing 16 and in front of the air inlet opening 20 can be readily changed to adjust the shape of the flame by inserting a screw driver or other suitable tool in the slot 26a formed in the end of the shaft 26 and rotating shaft 26 which is then held in its adjusted position by tightening the lock nut 27. Adjustment of the flame shaping baffle 25 will vary the amount of whirl or rotational momentum imparted to the air flow within the lateral air scroll 16.

The combustion air, with more or less whirl or rotational momentum imparted thereto within the lateral scroll casing 16, then passes in a plurality of equalized airstreams into the interior of the combustion air nozzle 15 through the slot openings between the three equilaterally disposed concentric segmental flow equalizing vanes 28. These segmental vanes 28 are located circumferentially and symmetrically about the axis of the scroll casing 16 directly at the entrance therefrom into the combustion air nozzle 15. These flow equalizing vanes 28 extend into engagement with the upright wall 17, thereby forcing all of the air admitted from the scroll casing 16 into the combustion air nozzle 15 to pass equally through the symmetrically centered spaces or slots between the vanes 28. These three slots serve to produce from the turbulent rotating air flow in the scroll three relatively equal and equally spaced air jets or streams which are admitted symmetrically about the axis of the air nozzle 15 and which will join to produce a uniform air distribution in the air nozzle 15.

In order to regulate or vary the amount of air passing through the spaces or slots between the vanes 28, the adjustable cylindrical sleeve 30 is slidably mounted inside of the combustion air nozzle 15 so that it may be positioned to equally close more or less of each space or slot between the flow directing vanes 28. The adjustable cylindrical sleeve 30 is arranged to be clamped in its desired position by means of the bolt 31 which extends through the slot 32 formed in the side wall of the combustion air nozzle 15. The bolt 31 is provided with the clamping wing nut 33 for securing the sleeve 30 fixedly in position. Upon loosening the wing nut 33, the sleeve 30 may be readily adjusted to close to the desired amount of each slot between the flow equalizing vanes 28.

The combustion air nozzle 15 is provided with a restricted outlet orifice 35 which preferably is formed in the end of a separate nozzle tip 36 which is detachably secured to the combustion air nozzle 15 by the bolts 37 in order that the nozzle tips may be readily replaced.

The oil atomizing nozzle 40, preferably of the improved variable oil rate form fully described and claimed in the patent application of Aldo Macchi, S. N. 320,558, filed concurrently herewith is provided for discharging atomized oil at variable rates into the combustion air stream adjacent the outlet orifice 35. It will be understood, however, that any well known means for varying the rate of oil supply to the flame may be employed if desired. The oil atomizing nozzle 40 preferably is mounted within the air cooling tube 41 and is supplied with oil and air under pressure through the pipes 42 and 43 respectively. The oil atomizing nozzle 40 is located co-

axially with the axis of the combustion air nozzle 15 and the cooling air tube 41 with the oil supply pipe 42 and air supply pipe 43 inside thereof extend through suitable openings formed in the upright wall 17 so that the pipes 42 and 43 may be connected to the electric motor driven oil and air supply means 12.

The atomized oil stream discharged at a desired rate from the nozzle 40 along the axis of the combustion air nozzle 15 preferably is ignited by means of an electric arc formed between the arcing electrodes 45 mounted in suitable high voltage insulators 46 in the supporting bracket 47 so as to locate the electric arc at the end of the electrodes 45 slightly above and adjacent the edge of the atomized oil stream issuing from nozzle 40. While not shown, it will be understood that the electrodes 45 are electrically connected through suitable conductors passing back through the upright wall 17 with a suitable ignition transformer located inside of the burner unit enclosing jacket or casing 10. Likewise while not shown in detail a flame detector switch operating mechanism 50 is mounted in the auxiliary housing 51 extending from the side of the combustion air nozzle 15 and made responsive to the presence or absence of combustion adjacent the end of the combustion air nozzle 15 by an improved air injector action as described and claimed in the aforesaid Macchi patent application, S. N. 320,557. The details of this improved flame detector arrangement are not deemed necessary to a proper understanding of the present invention and hence need not be further described except that it should be understood that the flame detector 50 operates with suitable automatic control mechanism mounted within the oil burner unit enclosing jacket 10 for insuring safe operation of the oil burner unit under all normal operating conditions.

In operation oil is supplied to the electric motor driven pumping mechanism through a suitable oil supply pipe line 52 shown in Fig. 2, electric power is supplied to the unit through a suitable power connection cable 53. Combustion air is drawn into the unit through the space under the upright wall 17 and between the edges of the enclosing jacket or casing 10 and then into the inlet opening of the electric motor driven blower 11. Upon ignition of the stream of atomized oil discharged at a desired rate from the nozzle 40 along the axis of the combustion air nozzle 15 and adjacent to the combustion air discharge orifice 35, a flame will be established and the general shape and size of this flame may be varied by means of the improvements of the present invention so as to conform with the various shapes and sizes of the combustion chambers of the furnaces to which the conversion oil burner unit embodying the present invention may be applied.

By adjusting the flame shaping baffle 25, the rotational component imparted to the combustion air flow through the scroll casing 16 may be varied between predetermined limits. The linear momentum component of the air flow through the combustion air nozzle 15 likewise may be varied between predetermined limits by adjusting the sliding sleeve 30 so as to close more or less of the slot openings between the flow equalizing vanes 28.

When a relatively short, wide angle flame from the burner unit is desired to fit a particular shape and size of furnace combustion chamber, the flame shaping baffle 25 is adjusted to its max-

num effective angular position as indicated in Figs. 2 to 4 so as to impart the desired maximum rotational momentum to the air flowing through the scroll casing 16 into the combustion air nozzle 15 through the slots between the equalizing vanes 28. This maximum rotational momentum of the air flow in the scroll 16 results from the displacement or crowding of the air flowing from the blower outlet 11a through the scroll inlet opening 20 away from the right-hand side of casing 16 which is the lower side as shown in Fig. 4. Such sidewise displacing or crowding of the air within the scroll casing 16 produces the permissible maximum counterclockwise whirl or rotation of the air flow passing through the slots between the vanes 28 into the combustion air nozzle 15 with the resulting rotational momentum component of the air at the air nozzle discharge orifice 35 serving to produce a relatively wide angle flame. The length of the flame may be regulated by adjusting the sliding sleeve 30 to the position indicated in Fig. 3 so as to reduce the effective area of the slots between the vanes 28 thereby materially reducing the linear momentum component of the air flow through the combustion air discharge nozzle orifice 35.

With no angular displacement of the flame shaping baffle 25, that is, with the baffle 25 in alignment with the air stream flow through opening 20, then the air flow through the scroll casing 16 will cause a substantially straight line radial air flow through the slots between the flow directing vanes 28. This will result in three equal jets of air, all radial, passing through the slots between the vanes 28 and joining into a uniform straight line air flow through the combustion air nozzle 15. This will result in producing an elongated relatively narrow flame the length of which may be regulated by adjusting the sleeve 30, the flame becoming longer as the sleeve 30 is adjusted to increase the area of the slots between the vanes 28.

Thus when the angular displacement of the flame baffle 35 is varied from that shown in Figs. 2 and 4 and the sleeve 30 is adjusted to vary the area of the slot between the vanes 28, the shape and size of the flame may be correspondingly varied to fit various shapes and sizes of combustion chambers to which conversion oil burner units embodying the present invention may be applied.

What I claim and desire to secure by Letters Patent of the United States is:

1. In a conversion oil burner for furnaces, the combination of combustion air supply means including a nozzle tube having air flow modifying means adjacent the outlet end thereof adapted to project a stream of air into a furnace combustion chamber, oil supply means including an atomizing nozzle mounted within said air nozzle tube adjacent said air flow modifying means, and air flow control means for varying the shape of the burner flame including a casing having a scroll surrounding the other end of said air nozzle tube and provided with an air inlet opening having an adjustable flow diversion vane for controlling the rotational component of air flow within said scroll, and an adjustable symmetrical multiported sleeve valve disposed inside said casing in alignment with said air nozzle tube for admitting a plurality of air streams from said casing into said tube and controlling the volume of said streams.

2. In a conversion oil burner for different size fire boxes, the combination of combustion air

supply means including a combustion air discharge nozzle tube, oil supply means including an oil atomizing nozzle mounted coaxially within said air discharge nozzle tube, and air flow control means for varying the shape of the burner flame including a scroll casing surrounding the inlet end of said air nozzle tube and provided with a side air inlet opening offset from the axis of said tube and a plurality of air outlet slots concentrically disposed symmetrically about the axis of said tube, adjustable flow diversion baffle means mounted adjacent said air inlet opening for controlling the rotational momentum component of the air flow within said scroll casing and an adjustable sleeve for equally varying the area of said air outlet slots.

3. An oil burner having, in combination, a combustion air nozzle tube, an air discharge nozzle tip at one end of said tube, a coaxial multiported air inlet sleeve valve at the other end of said tube for admitting a plurality of air streams symmetrically about the axis of said tube, an oil discharge nozzle mounted coaxially within said air nozzle tube adjacent said air nozzle tip, means for supplying oil under pressure to said oil discharge nozzle, means for igniting the oil discharged to establish a burner flame, a scroll casing surrounding said air inlet sleeve valve and having an air inlet opening provided with an adjustable baffle cooperating with said sleeve valve for controlling the rotational and linear momentum components of the air streams admitted to said air nozzle tube to vary the shape of the burner flame, and means for supplying air under pressure to said air inlet opening.

4. In an oil burner, the combination of air supply means including a combustion air supply tube having nozzle means at one end thereof adapted to project a stream of air into a furnace combustion chamber, oil supply means including an oil atomizing nozzle mounted within said air supply tube adjacent said nozzle means, peripheral air inlet means at the other end of said air supply tube for admitting a plurality of air streams symmetrically about the axis of said tube and having adjustable means for controlling the volume of said streams to regulate the size of the burner flame, and an air inlet scroll casing surrounding said peripheral air inlet means and having an adjustable baffle therein cooperating with said adjustable means for controlling the air streams admitted to said air supply tube to vary the shape of the burner flame.

5. In an oil burner adapted to be applied to furnaces having combustion chambers of different shapes, in combination, combustion air supply means including an air nozzle tube having symmetrical multiported peripheral air inlet means at one end thereof and air flow converging means at the discharge end thereof, oil supply means including an oil atomizing nozzle disposed within and adjacent to the discharge end of said air nozzle tube, a casing having a scroll surrounding said air inlet means and provided with an air inlet opening at one side of said air inlet means, and separately adjustable air flow control elements, one disposed adjacent said air inlet opening for controlling the rotational momentum component of the air flow within said scroll and another cooperating with said air inlet means for controlling the volume of the air admitted through said air inlet means from said casing to said air nozzle tube.

GAYLORD H. WOTRING.
